ELECTRIC CIRCUIT BREAKER

Daniel Rönnberg, Ludvika, Sweden, assignor to
 Allmänna Svenska Elektriska Aktiebolaget,
 Västeras, Sweden, a corporation of Sweden

Application November 9, 1937, Serial No. 173,585
 In Sweden November 14, 1936

6 Claims. (Cl. 200—150)

In electric circuit breakers, the arrangement of extinguishing pots surrounding the breaking gap, in which the arc is brought in intimate contact with a flow of an extinguishing liquid or gas, 5 has considerably increased the breaking ability of the circuit breakers. In spite of the fact that the provision of extinguishing pots of the above mentioned kind has considerably increased the breaking ability, however, no corresponding increase of the ability of the circuit breaker to close a current has been obtained, at least if the voltage has been high. This is due to the fact that when closing a circuit, at least when the voltage is high, an arc is lighted in the extinguishing pot, 10 and this causes a sudden shock of pressure, which if the current is high can be so powerful that the extinguishing pot will burst.

The pressure generated by an arc increases with the amount of heat generated by the arc, 20 and the amount of heat generated per unit of time is directly proportional to the product of the arc voltage and the current. The arc voltage in turn is proportional to the length of the arc and to the existing pressure. It is therefore clear 25 that the pressure arising in the first moment of closing of the circuit must be higher than the pressure arising at interruption of the circuit, because when the arc is lighted at closing the circuit, the contacts are at a rather great distance from each other whereas at the interrupting of the circuit, the arc is formed between the contacts when they are in immediate proximity of each other. If the breaking point is enclosed 30 in an extinguishing pot, the arc voltage and thus the pressure is further increased by the resistance against an equalization of the pressure depending upon the fact that the arc is enclosed in a comparatively confined space.

In order to increase the ability of a circuit breaker to close a circuit when the current is 40 large, it has previously been proposed to provide the circuit breaker with two series connected contact pairs, one of which has been enclosed in an extinguishing pot and chiefly intended for the opening of the circuit, whereas the other, which had for its purpose only to close the circuit, has been arranged outside the extinguishing pot. Instead of the provision of an auxiliary contact pair outside it, it has also been proposed to provide the extinguishing chamber with special members, by which the extinguishing pot has been opened when closing the circuit but closed when interrupting the circuit.

The present invention also refers to circuit 55 breakers of the kind provided with two contact

pairs, one of which the main pair has been arranged inside an extinguishing pot and intended for breaking the circuit, whereas the other contact pair the auxiliary pair intended for the closing of the circuit has been arranged outside the 5 extinguishing pot, but [in contradiction to the known circuit breakers, where the two contact pairs have been independently actuated by the operating mechanism] according to the present invention, one of the contact pairs is directly 10 operated by the operating mechanism and the other contact pair is operated by one of the contacts in the first-mentioned contact pair.

By the above arrangement of the contacts of the two contact pairs a very convenient and suitable form of circuit breaker is attained, especially with respect to the insulation, so that without any difficulties it can be adapted for high tensions. This is due to the fact that only one of the contact pairs is directly connected with the 15 operating mechanism. Further the auxiliary contact pair intended for the closing of the circuit may also be so arranged that it serves for interruption of the circuit in cooperation with the contact pair in the extinguishing pot. 25

On the accompanying drawing several forms of the invention are shown. Fig. 1 shows schematically one pole of a circuit breaker with one of the contacts of the main contact pair movable and connected with one of the contacts of the auxiliary contact pair which is arranged outside 30 of the extinguishing pot but inside a container enclosing the extinguishing pot.

Fig. 2 shows the auxiliary contact pair arranged below the extinguishing pot with one of 35 its contacts connected with the operating mechanism, and its other contacts connected with the movable contact of the main contact pair, the contact connected with the operating mechanism being provided with a piston which by the aid 40 of a liquid column actuates the main contact pair so that it is closed before the auxiliary contact pair is closed.

Fig. 3 shows a slight modification of the arrangement of Fig. 2. 45

Fig. 4 shows an extinguishing pot in which one of the contacts of the auxiliary contact pair is connected with a differential piston actuated by the pressure generated by the arc, this piston having the function to open the auxiliary contact 50 pair. In this form also an insulating wall is provided which has an opening traversed by one of the contacts of the auxiliary contact pair so that when opening the circuit breaker this contact is washed by a flow of fluid. 55

- Fig. 5 shows the same arrangement as Fig. 4 but with an additional differential piston which causes a flow of fluid against the arc between the contacts of the main contact pair.
- 5 Fig. 6 shows the same arrangement as Fig. 4 but with an additional differential piston which causes a flow of fluid through the wall traversed by one of the contacts of the auxiliary contact pair.
- 10 Fig. 7 shows a combination of the arrangements shown in Figs. 5 and 6 and is thus provided with two additional differential pistons.
- Fig. 8 shows in detail a vertical section of the arrangement shown schematically in Fig. 5, and
- 15 Fig. 9 is a detail section of the arrangement shown in Fig. 7.
- Fig. 10 is a detail section of a modified form of the arrangement schematically illustrated in Fig. 5.
- 20 In Fig. 1, 1 designates a container filled with an insulating medium. This container contains the two contact pairs and the bottom of the container is provided with an opening for the contact 2 operated by the operating mechanism of
- 25 the breaker. This contact extends in the closed position of the circuit breaker into the extinguishing pot 3, which consists of an upper cylinder 4 and a lower cylinder 5, which latter has a smaller diameter than the former. The extinguishing pot is closed at its lower extremity by a bottom 6 and at the top by a cover 7. In the double cylinder thus formed there is provided a differential piston 8, which at the top has a collar 9, which fits the cylinder 4 and at the bottom has a collar 10, which fits the cylinder 5.
- 30 The bottom 11 of the differential piston is of insulating material and is provided with an opening 12 for the movable contact 2. The stationary contact 13 is attached to a rod 14, which on the other end carries a contact 15. This rod extends through an opening 16 in the cover 7. Immediately above the stationary contact 13 is a piston 17 attached to the rod 14. The rod 14 is surrounded by a cylinder 18, which at the top has a cover 19 with an opening 20 for the rod 14. This cylinder has on the outer side a collar 21, which can be pressed tightly against the cover 7. The stationary contact 13 is normally held in its lower position by means of a helical spring 22, which at the lower end rests on the piston 17 and at the upper end against the cover 19 of the cylinder 18. This helical spring presses the cylinder 18 upwards so that the collar 21 is pressed against the cover 7. The cylinder 18 is provided with openings 23, the purpose of which is described below. The piston 17 has such a diameter that it tightly slides inside the cylinder 18. The extinguishing pot 3 is supported by the leading-in conductor 24 by means of a disc 25 and insulating rods or an insulating cylinder 26. In the case that 26 is a cylinder, this is provided with openings on the side. On the disc 25 a contact 27 is fastened, with which the contact 15 can be brought into engagement.
- 65 The arrangement acts in the following way. When closing the circuit breaker, the main contact 2 is moved upwards and is brought into engagement with the contact 13, which by a further movement of the contact 2 is moved upwards until the contact 15 auxiliary is caused to engage with the contact 27. When the contact 13 moves upwards, the fluid in the cylinder 18 is partly forced out through the openings 23 and thence through the space between the collar 21 and the cover 7 into the space 31. When opening the
- circuit breaker, the contact 13 is held back by the piston 17. When the piston 17 tends to move downwards, a vacuum is created on the upper side of it, so that the cylinder 18 is raised a little, and the collar 21 is tightly pressed against the cover 7. The opening of the circuit will therefore take place between the contacts 2 and 13 and the extinguishing pot will then act in the common manner, so that the pressure developed in it acts on the piston 8 which moves downwards thereby forcing the extinguishing medium from the space 32 through the opening 12 into the space 31, and at the same time extinguishing medium is forced out from the annular shaped space 33, which is in free communication with the outer container 1. The openings 30 in the cylinder 4 are so dimensioned that extinguishing medium may stream out through them, but they are so restricted that at the breaking a sufficient pressure can arise in the pot for moving the piston 8. The downward motion of the contact 13 is effected by the action of the spring 22. This downward motion is, however, so delayed that a vacuum is formed above the piston 17 due to the fact that, by the pressure in the pot, the collar 21 is pressed up against the cover 7. The tightening between this collar 21 and the cover 7 is not complete, however, and the time for the motion of the piston 17 will therefore depend upon the leakage between the collar 21 and the cover 7 and by the choice of a suitable leakage the separation of the contacts 15 and 27 can be so delayed that the interruption of the circuit will always be completed by the contacts 2 and 13. The container 1 is closed by a cover 34, which is provided with large openings for the escape of the gases. Instead of attaching the contact 13 on the rod 14, it is also possible to have it formed as a sleeve contact and attached to the cylinder 18. The movable contact 2 will in this case pass through the contact 13 up against the piston 17 thus moving it and the rod 14 until the contact 15 engages with the contact 27.
- 55 In the form shown in Fig. 2, 37 designates a cylinder with a cover 36. The stationary contact 35 is fastened to this cover. The cylinder 37 is provided with an inwardly bent edge 59, on which an insulating cylinder 38 is fastened. This cylinder 38 has an intermediary wall 39, which is provided with an opening for a contact 42. This contact is connected to a piston 43 movable in the cylinder 38, which piston also carries a contact 44, with which the contact 45 connected to the operating mechanism of the circuit can be caused to engage. The contact 45 carries a piston 46, which fits the cylinder 38. In the extinguishing pot formed by the cylinders 37 and 38 there is a differential piston 48 with bottom 49. This piston is normally held in its upper position by means of a helical spring 50. The cylinder 37 is provided on its side with openings 51 and in the same manner the cylinder 38 is provided with openings 52. The contacts 42 and 44 with piston 43 are normally pressed against the ring 41 by means of a helical spring 47.
- 60 This arrangement acts in the following way. When closing the circuit breaker, the piston 46 enters the cylinder 38, and as it moves upwards the fluid in the space 52 is moved upwards and moves the piston 43 so that the contact 42 is caused to engage the contact 35. At first after the contact 42 engages the contact 35 the piston 43 reaches the openings 50. The fluid pressed by the piston 46 will therefore, after it has served for the displacement of the contact 42, flow out 75

through the openings 40 and the contact 45 is on further upward motion caused to engage the contact 44. No pressure is thus developed in the extinguishing pot, and if an arc should ignite between the contacts 44 and 45, the gases generated thereby will escape through the openings 40. At the opening of the circuit breaker in the common manner, a pressure will arise in the extinguishing pot and will move the piston 48 downwards. The fluid enclosed in the space 56 will then stream through the openings 51, and as long as the contact 42 still occupies the opening in the intermediary wall 39, the fluid in the space 54 will flow out through the opening in the piston bottom 49 into the space 55, and at the further motion of the contact 45, the contact 42 is moved downwards by the helical spring 47, but when the piston 43 has reached the ring 41, the contact 42 can no longer move downwards. The upper tip of it will therefore remain immediately before the opening in the intermediary wall 39, which is the most advantageous position of the contact in relation to the opening in the intermediary wall in order to get the most favourable extinguishing conditions. As soon as the opening in the intermediary wall 39 is made free, liquid and gas from the extinguishing pot will be blown out through this opening and through the openings 40.

30 The arrangement according to Fig. 3 differs from the arrangement shown in Fig. 2 chiefly in that the differential piston is arranged around the extinguishing pot instead of inside it. The differential piston is in this case formed by the cover 36, which is provided with an opening for the rod 65, and by the cylinder 37, which is provided with an inwardly directed collar 59, which tightly fits the cylinder 63. This cylinder and the cylinder 60 with its collar are carried by the 40 rod 65.

The arrangement acts in the same manner as the arrangement shown in the preceding figure, so that the piston 46 forces the fluid in the space 52 upwards, which fluid then actuates the piston 43 until the contact 42 engages the stationary contact 35. With this motion, the contact 42 moves through the opening 62 in the insulating intermediary wall 61. When the piston 43 has moved a sufficiently long way, the space 52 is brought into communication with the space outside the cylinder 38 by the openings 40, so that the gases, which may be developed by an arc between the contacts 44 and 45 easily can escape. The pressure generated at the breaking is transmitted from the space 55 to the space 56, but also through the opening 62 to the spaces 54 and 57. The pressure generated by the arc moves the piston 36, 37 against the action of the helical spring 50, so that the space 57 is decreased, and the fluid in this space will therefore be forced through the openings 58 into the space 54 and from there through the channels 62 into the space 55. As in the preceding figure, the motion of the contact 42 is limited by the ring 41, so that also in this arrangement the tip of the contact 42 will stop in the position most suitable for the extinction. The arrangement may be such that the contact 42 in its end position rests in the opening in the bottom 64, but it is also possible to provide a form, where it moves so far that the opening in the intermediary wall 64 is free so that gas and liquid can escape through this opening.

In Fig. 4, 71 designates a cylinder of insulating material, which at the lower end is provided with a bottom 72 also of insulating material. This is

provided with an opening 73 for the movable contact 74. The other contact of the contact pair in the extinguishing pot is designated by 75, and this contact is by means of the cylinder 76 connected with the piston 77, which is movable in the cylinder 78. The piston 77 is actuated by a helical spring 81 and the space between the cylinders 76 and 78 communicates by means of a channel 80 with the space outside the extinguishing pot. The extinguishing pot is at the top 10 closed by an intermediary wall 83 of insulating material, which wall has an opening 82 for one of the contacts 79 of the contact pair outside the extinguishing pot. The other contact in this pair of contacts is designated by 84, and the space in 15 which the contact pair 79, 84 is contained communicates by means of large openings 85 with the space outside the extinguishing pot.

This arrangement acts in the following way. When opening the circuit breaker the contact 74 20 is drawn downwards, and then an arc is formed between the contacts 74 and 75. This generates in the extinguishing pot a pressure, which acts on the upper side of the piston 77, which moves downwards and pulls the contact 79 out of contact with the contact 84 and down through the opening 82. As soon as this opening has been 25 liberated, a flow of extinguishing medium in contact with the arc is caused between the contacts 79 and 84. There will therefore in this form be 30 two series connected arcs, one arc between the contacts 74 and 75 and one arc between the contacts 79 and 84, which arcs are extinguished by the extinguishing medium flowing through the openings 73 and 82 respectively.

The arrangement shown in Fig. 5 differs from that of Fig. 4 in that the extinguishing pot is provided with a differential piston 91, which in the bottom has an opening 92 for the contact 74. This differential piston is normally held in its 40 upper position by a helical spring 94, which at the lower end rests against the inwardly bent part 86 of the cylinder 71. This inwardly bent part carries also an insulating cylinder 87, which thus forms an extension of the extinguishing pot 45 and is closed at the lower end by a bottom 72 of insulating material. In this bottom there is a hole 90 for the contact 74 and back valves 89. In the cylinder 71 are openings 93 in order to allow the extinguishing medium below the flange 50 of the differential piston to escape from the extinguishing pot.

In the form shown in Fig. 6, the cylinder 87 instead of forming an extension downwards forms an extension upwards of the cylinder 71 and the 55 differential piston is in this form arranged in the upper part of the extinguishing pot so that by it a blow-out of the extinguishing medium through the opening 82 is effected. In the form of the circuit breaker shown in this figure the 60 same extinguishing action is obtained between the contacts 74 and 75 as in the arrangement according to Fig. 4, but at the contacts 79 and 84 a considerably increased extinguishing action is obtained by means of the powerful stream of extinguishing medium forced out through the opening 82 by means of the piston 91.

The arrangement according to Fig. 7 differs from the preceding one only in that the extinguishing pot is provided with two differential 70 pistons 91, of which the lower one causes an extinction of the arc between the contacts 74 and 75 and the upper an extinction of the arc between the contacts 79 and 84.

In Fig. 8 an arrangement principally the same 75

as in Fig. 5 is shown in detail. In this figure, 5 **101** designates the stationary contact in the extinguishing chamber and **102** the movable contact. The stationary contact is, however, to a certain extent movable and is connected with a differential piston described below. The extinguishing pot itself is formed by an insulating cylinder **103**, which is fastened to a metal cylinder **104**, which in turn is fastened to an annular 10 part **105** of metal, and this part is upwardly continued by an insulating cylinder **106**, fastened to a cover **107** carrying the extinguishing pot.

In the extinguishing pot there is a differential piston **108** consisting of an insulating cylinder **109** 15 with bottom **110**, which is also of insulating material and is provided with a flange **111**. The intermediary part **105** consists of a ring **112** and a ring **113**, which by means of arms **114** carries a nave **115**. In this nave a metal cylinder **116** 20 is inserted, and in this cylinder another cylinder **117** with a tightening ring **118** moves. The cylinder **117** also fits in a tightening ring **119** of the nave **115**.

The cylinder **117** carries the stationary contact **101**, which in a known manner is formed 25 as a sleeve contact, and further the cylinder **117** carries a pipe **120**, which at the upper end is closed by one of the contacts **121** in the auxiliary contact pair outside the extinguishing pot.

30 In the cylinder **106** there is an intermediary wall **122** with an opening **123**, through which the auxiliary contact **121** can pass on its way to its counter-contact **124**. The space in the cylinder **106**, which contains this contact is connected 35 by large openings **125** with the space outside the cylinder **106**, so that the contact pair **121**, **124** can be regarded as arranged outside the extinguishing pot.

Between the nave **115** and the cylinder **116** 40 there is a space **126**, which is in communication with the space outside the extinguishing pot through channels **127** in the arms **114**. These channels are provided with ball valves **128**, which allow liquid to enter the space **126**, but prevent 45 liquid escaping from this space. In one or a plurality of the channels in the arms **114**, the ball valves are replaced by plugs which seep holes of suitable size.

The ball valves **128** consist of a cylinder **129**, 50 which at the outer end is provided with an inwardly directed rand **130**. Immediately to this rand the cylinder is provided with two or several holes **131**, and in the cylinder there is a ball **132**, and the motion of this ball is outwardly limited 55 by the said rand, and its motion inwardly is limited by a pin **133**.

The space below the differential piston **108** 60 is on the drawings designated by **134** and the space above it by **135**, and further the space above the intermediary wall **122** is designated by **136**.

The arrangement acts in the following way. When closing the circuit breaker, the movable contact **102** is moved up against the stationary contact **101** and then moves the cylinder **117** with pipe **120** and contact **121** upwards, so that the latter is caused to engage the contact **124**. The closing of the circuit will therefore take place between the two latter contacts, and if then an arc is ignited, the gases generated by it will escape through the openings **125**. During the upward motion of the cylinder **117**, liquid is sucked into the space **126** through the ball valves **128**.

When opening the circuit breaker, the interruption of the circuit takes place between the

contacts **101** and **102**. The pressure then generated in the extinguishing pot acts on the differential piston **108**, so that it moves downwards. (Normally the piston **108** is held in its upper position by means of the helical spring **137**.)

The pressure in the pot also acts on the upper side of the bottom in the cylinder **117**. In fact, the cylinder **117** serves as a differential piston and tends to move downwards partly due to the pressure acting on it and partly due to the action of the helical spring **138**. This downward motion is, however, damped by the liquid in the space **126**, which liquid can escape only through the above mentioned seep holes in some of the arms **114**, and by regulating these seep holes the damping of the motion of the cylinder **117** can be regulated.

When the cylinder **117** moves downwards, the contact **121** is also moved downwards, and when it has passed through the opening **123**, here also an extinguishing action is added to the extinguishing action provided in the opening of the bottom **110**.

The damping of the motion of the contact **101** 25 is connected with the advantage that with small currents the distance between the contact **101** and the bottom **110** a longer time is maintained at a large value than if the current is large. The larger the current is the higher will be the 30 pressure in the pot and the faster will the cylinder **117** move downwards. In this way a smaller arc length is attained when the current is large, so that the energy developed by the arc during the interruption will be comparatively independent 35 of the magnitude of the current traversing the circuit breaker when interruption takes place.

The fact that the space covered by the larger 40 surface of the differential piston is opened and brought into communication with the space outside the extinguishing pot when the auxiliary contact moves downwards is followed by the great advantage that the piston in a shorter time can move back into the original position, 45 because the gas generated in the extinguishing pot can easily escape through the opening for the auxiliary contact as the pressure on both sides of the differential piston will then be equal. The helical spring **137** can move the piston back 50 to the original position without any great resistance.

The arrangement according to Fig. 8 is in some cases followed by the disadvantage that if an arc is ignited between the contacts **121** and **124** 55 before the contact **121** has reached the opening **123**, the pressure generated in the space **136** can be transmitted through the hole **123** and thus cause a motion of the piston **108**.

Fig. 9 shows in detail a form which principally 60 is the same as the form shown in Fig. 7. In this form the above disadvantage is eliminated since as in Fig. 7 a differential piston is arranged in the upper part of the extinguishing pot. This piston will cause a stream of extinguishing 65 medium through the hole **123** when the contact **121** is drawn away from this hole.

In Fig. 9, **101** designates the stationary contact and **102** the movable one. The extinguishing pot is formed by a cylinder **104**, which at the 70 lower end carries a cylinder **103**. The cylinder **104** is in turn carried by an intermediary part **105** consisting of a ring **112** and a ring **113**. The ring **113** carries by means of arms **114** a nave **115**. On the ring **113** a cylinder **139** is fastened, 75

which is continued upwardly by a cylinder 140, which is provided with an intermediary wall 122 with an opening 123 for the contact 121. The cylinder 140 is at the upper end closed by the cover 107, but the space 136 between the intermediary wall 122 and the cover 107 communicates by large openings 125 with a space outside the extinguishing pot. In the cylinders 104, 103 there is a differential piston 108, which consists of a cylinder 109 with bottom 110 and flange 111. In the cylinders 139 and 140 there is another differential piston 141, through which the contact 121 passes. The differential piston 108 is normally held in its upper position by means of the helical spring 137, and the differential piston 141 is normally held in its lower position by means of the helical spring 143. On the nave 115 a cylinder 116 is fastened. In this cylinder another cylinder 117 is movable. This carries at the lower end the stationary contact 101 and is at the upper end provided with a tightening ring 118, which slides in the cylinder 116. The nave 115 has at the lower end an inwardly bent part, which fits the cylinder 117, and further the cylinder 117 is provided with a rim 119, which tightening ring 118 slides in the cylinder 116. The cylinder 116 may have an inner diameter decreasing downwards, which diameter at the lowermost part of the cylinder 116 is the same as the outer diameter of the ring 119. The contact 101 is joined by means of the pipe 120 to the contact 121. The cylinder 117 with contact 101 is normally held in its lower position by means of the helical spring 138. The arms 114 are all, or only some of them, provided with channels 127, by which the space inside the nave 115 is in communication with the space outside the extinguishing pot, and further the cylinder 116 is provided with openings 151, which connect the space between the cylinder 116 and the cylinder 117 with the space inside the nave 115.

This arrangement acts in the following way. When closing the circuit breaker, the contacts 101 and 102 are brought into engagement with each other, and when the contact 102 moves upwards the contact 121 also is moved upwards through the hole 123, so that it is brought into engagement with the contact 124. The spring 138 is then pressed together.

When opening the circuit breaker, the contact 102 is pulled downwards and in the first moment the contacts 101 and 102 are separated. By means of the pressure generated by the arc formed between these contacts, the differential piston 108 is moved downwards and at the same time the differential piston 141 is moved upwards. The pressure generated by the arc between the contacts 101 and 102 acts at the upper side of the cylinder 117 and tends to move this cylinder with the contact 101 and the contact 121 downwards. This motion is, however, damped by the liquid enclosed in the space below the rim 119 between this rim and the lower inwardly bent part of the nave 115. This liquid must in escaping to the space outside the extinguishing pot pass the rim 119 into the space 126 and from there through the openings 151 and the channels 127. Due to the fact that the cylinder 116 inwardly has a downwardly decreasing diameter, the play between the rim 119 and the inner wall of the cylinder 116 will decrease when the cylinder 117 moves downwards, so that a successively increasing damping of the motion of the cylinder 117 is obtained. When the contact 121 is

moved so far downwards that the opening 123 has been liberated, the differential piston 141 forces extinguishing medium from the space 144 through the opening 123. A part of this extinguishing medium will traverse the bore 142 in 5 the contact 121 and from there out through the openings on the side of the pipe 120.

When closing the circuit breaker, the contacts 101 and 102 at first are brought into engagement with each other, and firstly after this contact is completed, the contact 121 commences the motion upwards. When an arc is then ignited between the contacts 121 and 124, the gases generated by this arc will escape through the openings 125.

The arrangement according to Fig. 10 differs from that of Fig. 9 in that the differential piston 141 is replaced by an intermediary wall 145, which is provided with openings 146, the said openings being closed by back valves 147. A 20 pressure generated in the space 144 therefore can not be transmitted to the space 135 and cause a motion of the piston 108. On the contrary, the pressure generated by the arc between the contacts 101 and 102 can if it is sufficiently high allow a flow of liquid from the space 135 out through the openings 146 into the space 144 and from there through the opening 123. The gases which are generated by the arc between the contacts 121 and 124 can escape 25 partly through the openings 125 and partly through the bore 148 and the openings 149 on the side of the pipe 124 out into the channels 150. In other respects the form shown in Fig. 10 is nearly the same as that shown in Fig. 9. 35

I claim as my invention:

1. In an electric circuit breaker an arc-extinguishing pot, a main contact pair enclosed in the said pot, an auxiliary contact pair arranged outside the pot and series connected with the 40 main contact pair, a dash pot mechanism retarding the opening of the auxiliary contact pair, an operating mechanism acting on the main contact pair, a spring acting on the auxiliary contact pair in the opening direction, and 45 a differential piston actuated by the pressure generated by the arc in the arc extinguishing pot, said piston being connected with one of the contacts in the auxiliary contact pair and acting in the opening direction. 50

2. In an electric circuit breaker an arc-extinguishing pot, a main contact pair enclosed in the said pot, an auxiliary contact pair arranged outside the pot and series connected with the main contact pair, a dash pot mechanism retarding the opening of the auxiliary contact pair, an operating mechanism acting on the main contact pair, a spring acting on the auxiliary contact pair in the opening direction, a differential piston actuated by the pressure generated by the arc in the arc extinguishing pot, 60 said piston being connected with one of the contacts in the auxiliary contact pair and acting in the opening direction, and an insulating wall of the arc extinguishing pot provided with 65 an opening traversed by the contact of the auxiliary contact pair connected with the differential piston.

3. In an electric circuit breaker an arc-extinguishing pot, a main contact pair enclosed in 70 the said pot, an auxiliary contact pair arranged outside the pot and series connected with the main contact pair, a dash pot mechanism retarding the opening of the auxiliary contact pair, an operating mechanism acting on the 75

- main contact pair, a spring acting on the auxiliary contact pair in the opening direction, a differential piston actuated by the pressure generated by the arc in the arc extinguishing pot,
- 5 5 said piston being connected with one of the contacts in the auxiliary contact pair and acting in the opening direction, an insulating wall of the arc extinguishing pot provided with an opening traversed by the contact of the auxiliary contact pair connected with the differential piston, and a further differential piston arranged inside the extinguishing pot causing a flow of fluid in contact with the arc between the main contacts.
- 10 10 15 4. In an electric circuit breaker an arc-extinguishing pot, a main contact pair enclosed in the said pot, an auxiliary contact pair arranged outside the pot and series connected with the main contact pair, means for closing the main contact pair and afterwards the auxiliary contact pair, a differential piston actuated by the pressure generated by the arc in the arc extinguishing pot, said piston being connected with one of the contacts in the auxiliary contact pair and with the stationary contact of the main contact pair, an insulating wall of the arc extinguishing pot provided with an opening traversed by the contact of the auxiliary contact pair, actuated by the differential piston, a retarding device for the motion of the differential piston, a further differential piston arranged inside the extinguishing pot causing a flow of fluid in contact with the arc between the main contacts, and a differential piston arranged inside the extinguishing pot, causing a flow of gases and liquid through the opening in the insulating wall of the pot, traversed by one of the contacts of the auxiliary contact pair.
- 20 20 25 30 35 5. In an electric circuit breaker with arc extinguishing pots, a main contact pair enclosed in each extinguishing pot, an auxiliary contact pair arranged outside the extinguishing pot and series connected with the main contact pair, means for closing the main contact pair and afterwards the auxiliary contact pair, a differential piston actuated by the pressure generated by the arc in the arc extinguishing pot, said piston being connected with one of the contacts in the auxiliary contact pair and the stationary contact of the main contact pair, an insulating wall of the arc extinguishing pot provided with an opening traversed by the contact of the auxiliary contact pair actuated by the differential piston, a retarding device for the motion of the differential piston, a further differential piston arranged inside the extinguishing pot causing a flow of fluid in contact with the arc between the main contacts, and a differential piston arranged inside the extinguishing pot, causing a flow of gases and liquid through the opening in the insulating wall of the pot, traversed by one of the contacts of the auxiliary contact pair.
- 30 35 40 45 afterwards the auxiliary contact pair, a differential piston actuated by the pressure generated by the arc in the arc extinguishing pot, said piston being connected with one of the contacts in the auxiliary contact pair and the stationary contact of the contact pair inside the arc extinguishing pot, an insulating wall of the arc extinguishing pot provided with an opening traversed by the contact of the auxiliary contact pair connected with the differential piston, a retarding device for the motion of the differential piston, a further differential piston arranged inside the extinguishing pot causing a flow of fluid in contact with the arc between the main contacts, and an insulating wall arranged inside the said insulating wall of the pot, provided with valves allowing a flow of gases and liquid only from the extinguishing pot to the space outside it.
- 20 25 30 35 40 45 6. In an electric circuit breaker with arc extinguishing pots, a main contact pair enclosed in each extinguishing pot, an auxiliary contact pair arranged outside the extinguishing pot and series connected with the main contact pair, means for closing the main contact pair and afterwards the auxiliary contact pair, a differential piston actuated by the pressure generated by the arc in the arc extinguishing pot, said piston being connected with one of the contacts in the auxiliary contact pair and the stationary contact of the main contact pair, an insulating wall of the arc extinguishing pot provided with an opening traversed by the contact of the auxiliary contact pair actuated by the differential piston, a retarding device for the motion of the differential piston, a further differential piston arranged inside the extinguishing pot causing a flow of fluid in contact with the arc between the main contacts, and a differential piston arranged inside the extinguishing pot, causing a flow of gases and liquid through the opening in the insulating wall of the pot, traversed by one of the contacts of the auxiliary contact pair.

DANIEL RÖNNBERG.
